A. H. Tingley,

Sawing Stone.

N° 11347

Patented July 18, 1854.

UNITED STATES PATENT OFFICE.

ALBERT H. TINGLEY, OF PROVIDENCE, RHODE ISLAND, ASSIGNOR TO HIMSELF, E. W. TINGLEY, AND H. F. TINGLEY.

IMPROVEMENT IN MACHINES FOR SAWING STONE AND MARBLE.

Specification forming part of Letters Patent No. 11,347, dated July 18, 1854.

To all whom it may concern:

Be it known that I, ALBERT H. TINGLEY, of Providence, in the county of Providence and State of Rhode Island, have invented a new and useful Improvement in Machinery for Sawing Marble or Stone; and I do hereby declare that the same is fully described and represented in the following specification, and the accompanying drawings and letters of reference thereon.

In the said drawings, Figure 1 represents a top view of a machine containing my invention. Fig. 2 is a front or side elevation of it. Fig. 3 is a side view of the secondary ratchet and its set of retaining-pawl, to be hereinafter described. Fig. 4 is a vertical and longitudinal section of the crank-shaft of the said ratchet and the machinery thereon, all of which will be hereinafter described.

The machine on which my improvement is made, or to which my invention is applicable, is in the main essentially like that described in the specification and drawings of Letters Patent granted to me on the 19th day of March, A. D. 1850.

In the drawings of this my improved machine, A represents a gang or series of saws fixed in a horizontal frame B, which, when in use, is suspended or placed directly over the block of marble or stone (seen at C) by means of four chains or cords D E F G, which, respectively, depend from and pass over four pulleys or guide-grooves, as seen at H I K L, made in two horizontal drums M N, that extend across and are supported on a frame O. The cords or chains are attached to a windlass P, which is arranged on the top of the frame O and midway between the two drums M N. The chains or cords are so applied to the windlass that when said windlass is turned in one direction it shall wind all of them simultaneously upon it, and when it is turned in the other direction it shall unwind them from it, the first operation serving to raise the gang of saws, while the last is for the purpose of depressing them.

On one end of the shaft of the windlass D there is a grooved pulley Q, to which one end of a cord R is fastened, the cord being wound around the periphery of said pulley, the other end of the said cord being fastened to and wound around a barrel R', fastened to a

sprocket-wheel S, the barrel and the sprocket-wheel being arranged as seen in the drawings, and made to turn on one common pin *a* or journal extended from the side of the frame-work. Above the periphery of the wheels S and that of a smaller sprocket-wheel U, disposed as seen in Figs. 1 and 2, an endless chain T extends around and imparts motion to the axle or crank-shaft *b* of said sprocket-wheel U. The said crank-shaft is supported on arms *c c*, projected from the main framework, and it has firmly fixed upon it a ratchet *d*. This ratchet has two pawls *e f* applied on opposite sides of it and connected by a connecting-rod *g*, said connecting-rod being jointed to the tail end of the pawl-lever *f*, and being connected to the opposite end of the other lever-pawl by means of a screw-pin extended through an elongated slot *h*, formed through said connecting rod or bar. Each pawl is pressed toward the wheel by means of a spring arranged as seen at *i k*. There is on the crank-shaft of the said ratchet another ratchet-wheel *l*, which is not fastened to the shaft *b*, but is applied to it so as to freely-rotate on it. There is also an arm *m* placed on the crank-shaft of the ratchet *l* and made to turn freely on the shaft. The outer end of this arm has a pin *n* extended through it, the pin being made to extend from each side of the arm. This pin carries a spring-pawl *o*, which is made to work into the serrated periphery of the last-mentioned ratchet. Such ratchet is provided with a pin *m'*, which extends from the front side of it, and during the rotation of the ratchet is successively carried into contact with each pawl of the other ratchet, so as to elevate said pawl from off its ratchet. These two pawls are arranged on their ratchets, so that when one is bearing against the radial side of one of the teeth the other is resting on the middle of the other angular side of the tooth on which it bears. Thus when each part is lifted the ratchet-wheel is set free, so as to be capable of being moved until the other ratchet comes in contact with the next tooth beyond it and arrests the motion of the wheel. The main ratchet of the crank-shaft is thus moved with an intermittent motion and imparts precisely such a motion to the crank-shaft and its sprocket-wheel U. By means of the endless

chain T the sprocket-wheel U conveys this intermittent rotary motion to its sprocket-wheel S, so as to cause it to turn its barrel and unwind the cord thereof, so as to allow the weight of the saw-frame to carry such saw-frame downward, the gradual depression of the saw-frame upon the stone during the reciprocating movement of the saw-frame for the purpose of sawing the stone being produced by such means.

To the pin n is jointed one end of a connecting-rod p , which at its opposite end is connected with a slotted arm of a bent rocker-lever q by means of a set-screw and nut r , the connecting-rod being made to turn freely on said set-screw, while the set-screw is fixed to the lever in such manner that it may be fastened in position in whatever part of the slot it may be. The extent of the reciprocating motion of the arm m may be increased or diminished by simply increasing or diminishing the distance of the set-screw r from the bent rocker-lever q . The upper arm of the rocker-lever q is jointed to one end of connecting-rod u , whose other end is jointed to a crank v , fixed upon one end of a horizontal shaft w , that receives motion from the main driving-shaft a' by means of two pulleys X Y and an endless belt Z. This driving-shaft has a fast and loose pulley fixed upon it, they being represented, respectively, by the letters b' c' , said shaft being supported by a frame-work e' . The driving-belt that puts the machine in operation is carried around the fast pulley. There is a crank d' fixed upon one end of the driving-shaft. The said crank has a connecting-rod e' jointed to it and extended from it toward and jointed to another crank f' , fixed upon a rocker-shaft p^2 . Said rocker-shaft has two arms or cranks f' g' extended in opposite directions from its middle part. A pitman or connecting-rod h' is jointed at one end to one or the other of the said arms, while at the other end it is jointed to the saw-frame B. The object of the two cranks or arms f' g' so extended in opposite directions above and below the shaft p^2 is to enable the connecting-rod or pitman of the saw-frame to be applied either to that one which is above the shaft p^2 when the saw-frame is above the level thereof, or the other of them when the said frame is below the level. If the pawls of the main ratchet, or that which is fixed to the crank-shaft of the sprocket-wheel U, are moved out of engagement with their ratchet, a person by laying hold of the crank of said shaft and turning will be enabled to quickly elevate or depress the saw-frame with respect to the stone as occasion may require.

Horizontally and transversely over the block of stone is a water-tube m^2 , which is supported in position by two tubes n' n' , which extend down from a shaft o' , to one end of which a water-hose may be attached for the purpose of leading water into the shaft, from whence it will flow from the tubes n' n' and

into the distributing-tube m^2 , the lower part of which is punctured with numerous fine holes for the purpose of allowing the water to fall down upon the saws or the stone while they (the said saws) are in operation. A reciprocating movement of the water-distributer is given to it by means of a connecting-rod p' and a crank q' , the rod being jointed to the crank, which is fixed on one end of a shaft w .

In Fig. 5 I have exhibited a side view of the water-distributer, wherein it will be seen that one of its tubes is provided with a series of hooked pins q^2 q^2 q^2 , placed one above the other. That end of the connecting-rod p' which operates the water-distributer is provided with a series of notches, as seen at r^2 , which notches are made to receive and rest upon either of the said hooked pins. By elevating the connecting-rod from pin to pin the extent of vibratory motion of the water-distributer may be proportionably increased, while by means of the notches in the connecting rod or bar the water-distributer may be set so as to play backward and forward over any particular portion of the upper surface of the stone which it may be desirable to have it play, rather than over the entire surface of it. We have thus a means of regulating the motion of the water-distributer and of causing that motion to take place over either a portion or the entire surface of the stone, as occasion may require.

Although the machinery which I have hereinbefore described is in many respects like such as is represented in Letters Patent to which reference has hereinbefore been made, it will be found that in other respects it differs from such and is much improved, the main difference being in the mechanism for gradually lowering the gang of saws during the operation of the sawing process.

What, therefore, I claim is—

1. The combination of the two spring-pawls, their slotted connecting-rod, the movable ratchet and its tripping-pin, with the fixed ratchet of the shaft of the sprocket-wheel U, the whole being operated and made to operate together, substantially in manner and for the purpose as specified.

2. The series of hooked pins on the water-distributer, in combination with the series of notches applied to the connecting-rod for operating the water-distributer, the whole being for the purpose of regulating the motion of the water-distributer and of causing that motion to take place over either a portion or the whole entire surface of the stone, as occasion may require.

In testimony whereof I have hereunto set my signature this 27th day of May, A. D. 1854.

ALBERT H. TINGLEY.
